UNITED STATES PATENT OFFICE

CONSTANTINE G. MILLER, OF CHICAGO, ILLINOIS

ELECTROPLATING MACHINE

Application filed December 22, 1928. Serial No. 328,031.

This invention relates to electro-plating machines, and particularly to automatic means for progressively subjecting articles to a series of cleaning and plating operations.

The main objects of this invention are to provide improved means for moving articles through plating baths at a required rate of speed for subjecting them to operations of predetermined duration, and for lifting them out of one bath and placing them into another at a faster rate of speed to avoid drying of the solution on the articles while they are exposed to the air; to provide an improved arrangement of horizontal conveying members and work transferring means and a common driving means for the same; to provide an improved construction of work carriers having arms of different lengths for creating a moment to urge the carriers firmly against a copper conductor plate, and to provide an improved means for alternatively connecting the carriers to the horizontal and vertical endless conveyor.

Further objects of this invention are to provide a full automatic, electro-plating machine, for progressively passing articles through a series of plating baths which is sufficiently flexible to be readily adapted for handling articles of different sizes without requiring replacement of expensive parts, to provide an improved construction and arrangement which will permit substantially the same general parts to be provided in machines for handling articles of various sizes, and to provide a machine of the class described which requires a minimum amount of floor space.

The objects of the present invention are in general accomplished by the employment of an endless traveling chain which is located in a horizontal plane for moving the articles through a series of different baths. A plurality of vertical conveying chains are provided for transferring articles from one bath to another. The vertical and horizontal chains are driven in synchronism with each other by a common driving shaft which is connected by gearing to a driving sprocket associated with each of the vertical traveling

chains respectively, and connected to a driving sprocket supporting the horizontal chain. The driving connection between the sprocket which actuates the horizontal traveling chain and the common driving shaft is through a worm which reduces the speed of movement of the horizontal traveling chain sufficiently to give the vertical chains time to pick article carriers from the horizontal chain, lift them and the articles thereon from one bath, lower them into another bath and deposit them on a bus bar in advance of that portion of the traveling chain from which they were lifted.

The horizontal traveling chain is supported between the sprocket wheels upon which it is mounted, by a track comprising channel or trough-shaped members. These channel members are provided with contact plates or strips of copper for receiving current from the article carriers.

The carriers are provided with an attachment member or shoe for alternatively connecting them to the horizontal and vertical traveling chains respectively. These shoes slide upon the edges of the copper contact plates or bus bars on the sides of the track and are provided with a groove for receiving an attachment on the vertical traveling chains when the horizontal chains bring the carriers into registration with the attachment. A slot is formed in the shoes for receiving a pin on the horizontal traveling chain. A flange or lug on each shoe having an inclined surface serves to guide the carriers into a proper position relative to the contact bus bars when the vertical traveling chains deposit them thereon, and also helps to retain a copper strip on the inner side of the carrier in contact with the side of the copper strip on the outside of the channels.

The articles to be plated are held by oppositely extending arms, the outer arm being longer than the inner arm, so as to create a moment for urging the side of the carrier having the copper bus bar thereon against the copper plate of the channel member when articles of the same weight are carried by the arms. This arrangement serves to effectively stop the work supports

and articles carried thereon from swinging during the transfer from tank to tank and thus overcomes this common difficulty.

In the accompanying drawings I have 5 illustrated a specific embodiment of my invention, in which:

Fig. 1 is a side elevation of a plating machine.

Fig. 2 is a top plan thereof.
10 Fig. 3 is an end elevation at the driving end.

Fig. 4 is a fragmentary vertical section of the trough-shaped track showing a conveyor therein.

15 Fig. 5 is a transverse section taken on the line 5—5 of Fig. 1.

Fig. 6 is a fragmentary detail of a driving sprocket and a horizontal conveyor member.

20 Fig. 7 is a fragmentary section taken on the line 7—7 of Fig. 6.

Fig. 8 is a transverse section of a trough-shaped track showing a conveyor therein and a carrier mounted thereon.

25 Fig. 9 is a perspective detail of a carrier shoe.

Fig. 10 is a fragmentary elevation showing a carrier in a changed position.

In the form shown in the drawings, a plating machine comprising spaced end columns 30 1 and 2, and an intermediate top frame 3 extending therebetween is provided with a continuous track 4' comprising channel-shaped members located below the top frame 35 and supported thereby on the vertical angle members 4.

30 Sprockets 5 and 6 are mounted within the framework of the columns 1 and 2 respectively on vertical shafts 7 and 8 respectively. 40 The track 4' extends around the outer peripheries of both of the sprockets 5 and 6 and a conveying chain 9 extends around both of the sprockets 5 and 6 and as shown in Fig. 8, is confined within the channel-shaped track 4'.

45 The chain 9 is provided with a plurality of rollers or castors 10 which rest upon the bottom of the track and which may be suitably positioned on the chain for supporting the same. Each link is provided with a socket 50 for removably supporting a pin 11. The pins 11 may be arranged in any sequence on the chain 9 as, for example, on every third link as shown in the drawing, and they may be 55 altered in position as required in adapting the chain 9 for moving articles at a different speed or through different distance as hereinafter set forth.

Spaced sets of sprocket wheels 12, 13, 14 10 and 15 extend beyond the sides of the intermediate frame 3 and each set of sprocket wheels is provided with a continuous chain 16. The sprocket wheels 12 are carried by horizontal shafts 17' which are provided at 65 their inner ends with beveled gears 18. All

of the sprocket wheels 12, 13, 14 and 15 are located in substantially the same vertical plane and the chain thereon is therefore adapted to lift articles up and lower them in the manner hereinafter set forth. Any desired number of chains 16 may be provided along both sides of the track 4' by equipping the machine with a suitable number of sprocket wheels.

70 The horizontal conveyor chain 9 and the vertical conveying chains 16 are driven in synchronism with each other by a motor 17 mounted on the top of the column 1. The motor 17 is operatively connected by a chain 18' to a shaft 19 upon which a pulley wheel 20 is rigidly mounted.

The pulley wheel 20 is operatively connected by a belt 21 to a shaft 22, which in turn is connected to a main shaft 23, extending longitudinally of the center of the machine at the top thereof, by a chain 24. The main shaft 23 is provided with spaced beveled pinions 25 which mesh with the beveled gears 18 of each set of sprocket wheels which support the vertical conveying chains. All the vertical conveying chains may be 80 driven in unison at the same speed or at different speeds by employing bevel gears of different sizes to maintain the synchronism of the horizontal and vertical chains when the distances between pick-up and set-down positions of the vertical chains are different. As

85 all the bevel gears 18 of the driving sprockets 12 of one side of the machine are on the same side of the pinion 25, and the beveled gears 18 of the driving sprockets 12 of the opposite side of the machine are on the other side of the pinion 25, it should be understood that the conveyor chains 16 of opposite sides of the machine travel in opposite directions.

90 A gear 26 on the main shaft 23 meshes with a gear 27 on a shaft 28 which carries a worm confined in a housing 29. This worm drives a worm gear on the vertical shaft 30. The vertical shaft 30 is provided with a pinion 31 which meshes with a gear 32 on the vertical shaft 7 of the sprocket 5. The sprocket 5 is 95 driven by the main shaft 23 through the above chain of gears and by reason of the worm drive, moves the horizontal conveyor chain 9 at a slower rate of speed than the movement of the vertical chain 16. The shaft 8 of the sprocket 6 is carried by an adjustable bearing member 33 which may be adjusted in position by the nuts 34 on the threaded member 35 to produce the proper amount of tension in the horizontal conveying member 9.

100 Article carriers for moving articles to be plated through a series of cleaning and plating baths are provided comprising angle irons 36 and arms 37 and 38, the outer arm 37 being longer than the inner arm 38. A strip of copper 39 is attached to the inner sides of the angle irons 36, for effecting an electrical connection between the articles being plated, and copper contact plates 40 and 41 rigidly at- 105

tached to the sides of the channel-shaped tracks 4'. These carriers comprise a head member or shoe 42 preferably consisting of brass. Each shoe is provided with a slot 43.1 for receiving one of the pins 11 of the horizontal conveying chain 9, a groove 43 formed in an angle-shaped housing 44 on the inner end of the shoe and a lug 46 extending downwardly from the bottom plate 47 thereof. 5 The bottom plate 47 rests upon the upper edges of the contact bus bars 40 and 41 and the shoe together with the carrier is moved horizontally along the track by the conveying member 9. An attachment 48 is positioned 10 on each of the vertical conveying chains 16, so as to register with the groove 43 when the shoe 42 reaches a position adjacent the upwardly moving side of said chain.

When the plating machine is in operation, 20 an attendant standing at either end thereof, for example the end comprising the column 1, places articles to be plated on the arms 37 and 38 of each carrier. As the arm 37 is longer than the arm 38, a moment is created 25 which tends to urge the angle irons 36 of the carrier inwardly and firmly holds the copper strips 39 in engagement with the contact strip 40 on the track 4'. An article carrier may be mounted on each pin 11 of the horizontal conveying chain 4' or on alternate 30 pins if desired.

The conveyor chain 9 is driven in the direction of the arrow 50, thus moving the carriers shown in Fig. 1 to the right. Any desired number of plating, cleaning or rinsing baths may be provided in receptacles such as tank 51 positioned below the intermediate frame 3 of the machine and the articles to be plated may be successively moved through 40 these baths by the chain 9, and lifted out of one and placed into the next adjacent bath by the vertical conveying chains 16.

The left side of the vertical conveying chains moves upwardly as viewed in Fig. 1 45 and when an attachment 48 thereon engages in the groove 43 of a carrier shoe 42, the latter is lifted off of pin 11 of the chain 9. The pin from which a particular carrier has been removed continues to move along to the 50 right and the carrier, together with the articles thereon is lifted by the chain 16, moved horizontally from one side of the locus of the chain to the other side of said locus and is then lowered and placed on the bus bars 40 and 41 and over a pin 11 of the chain 9 located in advance of the pin from which it was previously lifted, it being understood that the chain 16 moves at a greater speed than the chain 9, thus permitting proper placement 55 of the carrier relative to the chain 9. In this manner the articles are lifted vertically from one tank, rapidly moved to a position above the next adjacent tank, so as to avoid drying of the plating or cleaning solution 60 thereof, and deposited in the latter tank.

The lugs 46 guide the shoes into proper position relative to the contact strip 40 when the carrier is placed thereon and prevent endwise movement of the carrier. The horizontal chain 9 continues to move to the right as viewed in Fig. 1, until shoe 42 registers with an attachment 48 of another vertical conveying chain.

The carriers proceed around the entire course of the track 4, moving from left to right on the side of the machine shown in Fig. 1, and from right to left on the opposite side of the machine, until they return to their starting position, where they may be detached from the arms 37 and 38 by the same attendant, who places other articles thereon to be plated.

In the construction of the above described plating machine, it is possible to predetermine the lift effected by the chains 16 to correspond with the length of the articles to be plated without requiring changes in the major portions of the device. In this event, more links are added to the chains 16 and the upper and lower sprocket wheels of each series are spaced a greater distance apart. The speed of movement of the chains 16 and 9 may be changed without affecting their synchronism by changing the gearing and properly positioning the pins 11 so that they are timed to bring a carrier into registration with the attachments 48 of the vertical chains when the latter commence their upward travel, thus predetermining the duration of the plating operations to which the articles are subjected.

The dimensions of the slots 43 of the shoes 42 exceed the diameter of the pins 11 sufficiently to permit placement of the shoes on the latter when the synchronism of the horizontal and vertical conveying members is varied by stretching of the chains and the spread of the gable-shaped portions 44 of the shoes allows the carriers to be properly lifted when the timing of the movements of the vertical and horizontal conveying members is varied in the above manner.

Although but one specific embodiment of this invention has been herein shown and described, it will be understood that details of the construction shown may be altered or omitted without departing from the spirit of this invention as defined by the following claims.

I claim:—

1. In a plating machine, a supporting structure comprising spaced end columns and an intermediate structure, a continuous loop shaped trough extending between said columns and located in a substantially horizontal plane, an endless conveyor movably mounted in said trough comprising spaced upright pins, article carriers removably supported on said trough, each comprising a shoe having a slot therein for receiving one

- of said upright pins, and spaced endless vertical traveling members mounted on said intermediate structure comprising projecting rollers for engaging a groove in the shoes of said carriers to intermittently lift the carriers from said longitudinal conveyor and replace them thereon in advanced position for facilitating the transfer of articles from one plating tank to another.
2. In a plating machine, a supporting structure comprising spaced end columns and an intermediate structure, a continuous loop shaped trough extending between said columns and located in a substantially horizontal plane, an endless conveyor movably mounted in said trough comprising spaced upright pins, article carriers removably supported on said trough, each comprising a shoe having a slot therein for receiving one of said upright pins, spaced endless vertical traveling members mounted on said intermediate structure comprising projecting attachments for engaging a groove in the shoes of said carriers to intermittently lift the carriers from said longitudinal conveyor and replace them thereon in advanced position for facilitating the transfer of articles from one plating tank to another, and a common driving means for driving said horizontal and said vertical traveling members in synchronism with each other, for effecting replacement of the shoe member of said carriers on pins in advance of the pins from which they were lifted.
3. In a plating machine, a frame comprising a loop-shaped trough, contact strips on the sides of said trough, an endless conveyor movably mounted in said trough comprising upright pins, article carriers comprising a shoe member slidably mounted on said contact strips having a slot therein for receiving one of said pins, means mounted on said frame for intermittently lifting said carriers from said conveyor and raising the same to transfer articles thereon from one plating tank to another, and lugs on said shoe members for facilitating replacement thereof on said contact members and for holding the sides of said carriers in engagement therewith.
4. A plating machine comprising a frame, a continuous track on said frame comprising a channel shaped track, a conveyor mounted on said track, electric contact plates on the sides of said track, article carriers slidably mounted on said contact plates comprising a shoe member, a lug on said shoe member for preventing displacement thereof relative to said track, and arms in the lower ends of said carriers for attaching articles thereto, the outermost arm of said carrier being longer than the innermost arm thereof for creating a moment to urge the side of said carrier against one of said contact plates.
5. A plating machine comprising a sup-
- porting structure, a track on said supporting structure comprising a channel-shaped member, contact plates on the sides of said track, a carrier slidably mounted on said track comprising a transverse shoe extending across said track and resting upon said contact plates, and a lug on said shoe for engaging the inner side of one of said contact plates for preventing sidewise movement of said carrier relative to said track and for facilitating placement of said shoe on said contact plates in a predetermined position.
6. A plating machine comprising a supporting structure, horizontal and vertical conveying members on said structure, a track mounted on said structure comprising contact plates, a carrier comprising a shoe suspended from said track, said shoe being slidably mounted on the edges of said plates and being provided with a slot and a groove for facilitating attachment of said carrier to said horizontal and vertical conveying members respectively, contact strips on the inner side of said carriers for engaging a contact plate of said track, and supporting arms on said carriers, the outer supporting arm being longer than the inner arm for frictionally engaging said contact plate and the contact strip of said carrier to prevent swinging thereof when it is transferred from said horizontal to said vertical conveying member.
7. In a plating machine a frame comprising a track, a horizontal conveying chain mounted on said frame in close proximity to said track comprising links having sockets therein, vertical conveying chains mounted on said frame each comprising an attachment member, driving means on said frame operatively connected with said vertical and horizontal chains, article carriers slidably supported on said track, and pins removably mounted in the sockets of said horizontal chain links for intermittently moving said carriers along said track and adapted to be suitably positioned for various relative speeds of said vertical and horizontal chains for moving said carriers into registration with the attachment members of said vertical chains to effect intermittent transfer thereof to said vertical chain.
- Signed at Chicago this 19th day of December, 1928.
- CONSTANTINE G. MILLER.
